UNITED STATES PATENT OFFICE.

SOLOMON GROLLMAN, OF CHICAGO, ILLINOIS.

DESIGN FOR A PIANO-CASING.

SPECIFICATION forming part of Design No. 25,393, dated April 14, 1896.

Application filed November 15, 1895. Serial No. 569,117. Term of patent 14 years.

To all whom it may concern:

Be it known that I, SOLOMON GROLLMAN, a citizen of the United States, residing at Chicago, in the county of Cook and State of Illinois, have invented and produced a new and original Design for a Piano-Casing, of which the following is a specification, reference being had to the accompanying drawings, in which—

- 10 Figure 1 illustrates a view in front elevation of the piano-casing, and Fig. 2 represents a side view of the same.
- 15 A represents the upper body portion, and B the lower body portion of an upright-piano.
- 20 The front and ends of the keyboard portion C are ornamented to represent a molding, and said keyboard portion or extension is braced and supported by ornamented posts c c' and cheek-plates d d'.
- 25 The upper and lower front panels D D', respectively, and the end panels E are provided

with scroll ornamentation, as shown in the drawings.

The leading feature of my design consists in the configuration placed or formed upon 25 the front and end panels of the casing and also in the configuration of the design upon the cheek-plates and the supporting-post for the key-bed, the design intending to be covered relating to the whole general appearance 30 of the casing.

What I claim is—

The design for a piano-casing substantially as hereinbefore set forth and shown in the accompanying drawings.

In testimony whereof I have hereunto set my hand, this 31st day of October, A. D. 1895, in the presence of two witnesses.

SOLOMON GROLLMAN.

Witnesses:

L. W. BULKLEY,
CHAS. C. BULKLEY.
